DESIGN FOR A PAIR OF SEMIRIMLESS
SPECTACLES

John J. Rohrbach, Rochester, N. Y., assignor to
Shuron Optical Company, Inc., Geneva, N. Y.,
a corporation of New York

Application July 24, 1941, Serial No. 102,449

Term of patent 14 years

To all whom it may concern:

Be it known that I, John J. Rohrbach, a citizen of the United States, residing in Rochester, county of Monroe, and State of New York, have invented a new, original, and ornamental Design for a Pair of Semirimless Spectacles, of which the following is a specification, reference being had to the accompanying drawing, forming part thereof.

In the drawing:

Figure 1 is a perspective view of a pair of semirimless spectacles, part of one temple being broken away, showing my new design;

Figure 2 is a top plan view thereof; and

Figure 3 is a section on an enlarged scale, part being broken away, taken on the line 3-3 of Figure 2.

The essential features of my design are shown in full lines in Figures 1 and 2. My design for a pair of semirimless spectacles, as shown, is characterized by (1) temples and lens support-

ing top arms of plastic material; (2) end pieces and lens supporting lugs of exposed or bare metal; (3) said top arms being shaped to correspond substantially to the contour of the upper edges of the lenses to be supported and being positioned rearwardly of the lenses and projecting a substantial distance above the upper edges of said lenses, as best shown in Figure 3; and (4) the forward ends of the temples curving around in front of the metal end pieces and abutting against the end pieces and concealing the same from the front. Metal strengthening members or core wires of a shape best seen in Figure 3 are illustrated within said temples and top arms.

I claim:

The ornamental design for a pair of semirimless spectacles, substantially as shown and described.

JOHN J. ROHRBACH.
